REPERFORATOR

James A. Spencer, Teaneck, N. J., and Thomas J. Merson, Hollis, and Lewis A. Thomas, Brooklyn, N. Y., assignors to Radio Corporation of America, a corporation of Delaware

Application February 15, 1947, Serial No. 728,850

7 Claims. (Cl. 178—92)

1

This invention relates to telegraph apparatus and mechanisms and more particularly to an improved method of recording received telegraph code impulses on a perforated tape.

In modern telegraph practice it is frequently advantageous to store received code signals in a perforated paper tape in order that re-transmission may be accomplished at a later time. Devices of this kind are referred to as "reperforators." This reperforator is designed primarily for reception of Morse signals transmitted approximately synchronously, but it will also reproduce accurately non-synchronous signals transmitted at a rate lower than the regular signalling speed, such as when "breaks" are inserted by hand in an automatic transmission sequence.

In the present practice perforators of this type require a complicated system of cams operated by a motor for differentiating between dots and dashes. The Creed reperforator described in Harrison's "Printing Telegraph Systems," page 208, is an example of this type of reperforator.

The perforator provided by this invention does not require such cams or motor since it is required to recognize or perforate only the start and end of a marking signal. The perforator punches feed holes as well as code holes. Accordingly, it requires no specially prepared tape, but will operate with a standard transmitting tape.

It is an object of this invention to provide a reperforator which will perforate a tape directly from received signals having mark and space elements.

It is a further object of this invention to provide a reperforator of the type described in which the mechanical parts have been reduced to a minimum.

Briefly, in accordance with the invention, the incoming signals are utilized to produce negative and positive pulses during the transitions from mark to space and space to mark, respectively. A local source of oscillations synchronized with the incoming signals is utilized to actuate the perforator and the pulses produced during the transition periods are utilized to actuate the proper mark or space punch of the perforator.

The above and other objects and advantages of the invention will become apparent upon a consideration of the following detailed description taken in conjunction with the accompanying drawings, in which:

Fig. 1 represents schematically a preferred em-

bodiment of the invention for producing the controlled potentials for actuating the perforator.

Fig. 2 is a diagrammatic representation of one form of perforator for use with the chosen embodiment of the invention, and

Fig. 3 represents the time occurrence of the actuating pulses and the form of the tape produced therefrom.

Referring to Fig. 1, means have been provided so that the device will operate from an electrical or electronic source of keyed signals. Thus when a keyed-tone signal is being received, a tone signal converter, not shown, is used and its output is fed to the SIG terminal and switch 14 is thrown to the SIG position. When an external polar relay is provided, switch 14 is thrown to the EXT relay position.

A polar relay 23, together with its associated components, resistors 24, 25 and 26 and capacitors 29, form an oscillating circuit known as the Gulstad relay. This is a circuit old in the art whose frequency of oscillation can be controlled, up to the speed capacity of the relay itself, by varying the values of resistors 26 and capacitors 29. The coil of a second polar relay 27 is inserted in series with the oscillating circuit so that this relay will oscillate in synchronism with relay 23 and, as will appear, certain further functions can be performed without affecting the oscillating circuit.

Whenever the tongue of relay 27 is held to the right-hand terminal, capacitor 31 will charge to approximately full positive value through resistor 28. When the tongue of relay 27 swings to the left, the energy stored in the capacitor 31 is discharged through the coil of relay 3, closing relay 3 momentarily. Thus relay 3 is closed once for every oscillation of relay 23.

The signals applied to the SIG terminal are fed through an electronic discharge device 12, the output of which is utilized to control a polar relay 13. The polar relay 13 is phased so that for every marking signal the tongue of relay 13 will be connected to the positive voltage through resistor 15, and for every spacing signal the tongue will be connected to the negative voltage through resistor 16.

Whenever the tongue of relay 13 is positive, a conductive path is formed through resistor 15, capacitor 17, rectifier 18 and the coil of relay 1 to ground. Capacitor 17 rapidly becomes charged so that the current through relay 1 is merely an impulse tending to close relay 1 momentarily at the beginning of every marking signal. It will be seen that the rectifier 18 con-

sists of a pair of rectifying paths oppositely connected to the capacitor 17. Thus, whenever the tongue of relay 13 becomes negative, a conductive path is formed through resistor 16, capacitor 17, rectifier 18 and relay 2 to ground. Capacitor 17 will thus be rapidly discharged and charged in the opposite sense causing an impulse tending to close relay 2 momentarily at the end of every mark signal.

When the tongue of relay 13 is positive, a parallel path is set up through resistor 15, capacitor 19 and rectifier 20 and a coil 22 of relay 23 to ground. The rectifier 20 is so connected that at the beginning of every marking signal the pulses produced across capacitor 19 will be sent through coil 22. The coil 22 is magnetically coupled to the relay 23 in the proper phase to tend to speed up the oscillating frequency of relay 23 by a slight amount. Since the relay 23 is normally adjusted to have a speed of oscillation slightly less than the dot repetition rate of oscillation, the closure of relay 3 will occur simultaneously or slightly after the closure of relay 1. The reason for this action will be seen presently.

Switch 30 is arranged so that the oscillating frequency of relay 23 can be set to correspond with the dot repetition rate of the incoming signal, with no correction applied, and then, with the application of correction, the frequency of oscillation is automatically reduced a slight amount, this intentional difference being taken care of by the correction. This feature allows for a certain amount of variation in the speed of the incoming signal due to the use of non-synchronous motors in transmission.

The mechanical action of the reperforator will be described in connection with Fig. 2. Relays 1, 2 and 3 have contacts which are in effect parallel switches on the operating circuit of the solenoid or punch magnet 9. Thus, solenoid 9 is energized with the closure of any of the relays 1, 2 or 3. Solenoid 9 swings punch block 10 forward against the end of punch pins which are driven through the tape 32. The center hole pins 8 are arranged to be operated with every operation of solenoid 9. The top or mark hole pin 6 is operated whenever the vane 4 is interposed between the block 10 and the end of pin 6. Vane 4 is actuated by a mechanical linkage with the armature of relay 1. Thus the mark pin 6 will be operated whenever relay 1 is energized. In order that the punch block 10 not operate before vane 4 is selected, the relay 3, as described above, is made to operate slightly later than relay 1.

A similar linkage from the armature of relay 2 interposes vane 5 between the block 10 and the end of the bottom hole or space pin 7. A slight delay in the sequence of operation of relays 2 and 3 is provided for in the same manner as that between the operation of relays 1 and 3. In order that the tape will be punched as standard Morse Wheatstone tape, both the relative positions of the four punch pins and the operation of the tape advance are important. As is clearly shown in Figure 2 by the arrangement of the guide holes, 38, 39, 40, for the punch pins in the tape guide 41, the center hole pins 8 are arranged in horizontal alignment; the mark pin 6 is disposed above and in vertical alignment with one of said center hole pins; and the space pin 7 is disposed below and in vertical alignment with the other of said center hole pins.

After each operation of relay 1 or 3, extraction of the punch pins from the tape is accomplished

by means of springs, not shown. A standard wheel and pawl mechanism 11 advances the tape one center hole. An additional mechanical linkage on the armature or relay 2 is provided to disable the tape advance mechanism 11 whenever relay 2 is operated. This provision is made because of the fact that the distance between the center holes of the tape is equal to one keying cycle or two bauds. The end of the mark always occurs at an odd number of bauds later than the start of mark, or between times of tape advance, and each start of mark occurs an even number of bauds after the previous start of mark. Thus, by the proper positioning of the punch pins and the proper operation of the tape advance, standard Morse Wheatstone tape is punched from the incoming signal.

The operation of the device may best be understood upon a consideration of Fig. 3; in which, there is represented a line a, three letters RCA of a code group followed by an interval representative of the spacing between code groups which in turn is followed by the letter T. Line b represents the pulses, produced by the circuit shown in Fig. 1, which operate relay 1. As has been described, these pulses will be produced at the start of every mark signal. Line c represents the pulses produced from the local oscillator circuit which operates relay number 3. Line d represents the pulses produced at the end of the mark signal which, as has been described, operate relay number 2.

Thus, at the start of the code signal representative of the letter R, the local oscillator generates a pulse which will energize relay number 3 and at the beginning of the mark signal a pulse will be produced which will energize relay number 1. The energization of relays 1 and 3 results in the punch block perforating feed holes 33 and 34 and the mark hole 35. Upon the withdrawal of the punch pins, the tape will be advanced one space. At the end of the mark signal, which in the assumed case was a dot and would occur one dot interval later, relay 2 would be energized causing the operation of the center hole pin 8 and the space pin 7. This results in the perforation of feed hole 36 and space hole 37. During this operation the tape advance mechanism will be deenergized and the tape will not be advanced. The remainder of the code signals will be perforated in a similar sequence of operations with the dots, dashes and intervals being represented by various spacings produced by combinations of relays 1 and 3, 2 and 3 or only 3.

If a radical change in speed takes place in the transmission, such as the insertion of "breaks" by hand, the reperforator will faithfully reproduce the signal to the nearest center hole, since the punch of the center hole occurs at a constant rate or during long marking or spacing signals.

Having described our invention, what we claim is:

1. A perforator comprising, in combination, a feed hole punch, a mark punch, a space punch, a punch block, holes in said punch block, said holes being in alignment with said mark and space punches whereby movement of said punch block causes operation of only said feed hole punch, means interposable between said mark punch and the corresponding hole in said punch block whereby movement of said punch block actuates both said feed hole and mark punches, means interposable between said space punch and the corresponding hole in said punch block whereby movement of said punch block actuates said center hole and space punches, a tape arranged to be

perforated by said punches when said punches are actuated, a tape advance mechanism normally arranged to advance said tape upon each actuation of said punch block and means arranged to disengage said tape advance mechanism when said space punch is actuated.

2. Electrical apparatus comprising, in combination, a source of code signals, a local source of oscillations, means independent of said source of oscillations for producing a positive pulse upon the transition of said signals from space to mark and a negative pulse during the transition of said signals from mark to space, a first relay actuated by said positive pulse, a second relay actuated by said negative pulses, a third relay actuated under the control of said local source of oscillations, means for synchronizing said local source of oscillations with said signals, a punch block actuated upon the energization of any of said relays, a first punch, a second punch, a third punch, said punch block normally actuating only said first punch, means actuated by said first relay causing said punch block to actuate both said first and second punches, means actuated by said second relay causing said punch block to actuate said first and third punches, a tape, said tape being arranged to be perforated by said punches, a tape advance mechanism normally arranged to advance said tape upon each actuation of said punch block, and means controlled by said second relay for disengaging said tape advance when said first and third punches are actuated.

3. Electrical apparatus comprising, in combination, a source of code signals having mark and space elements, a local source of oscillations, switching means independent of said source of oscillations for producing a positive potential during mark elements and a negative potential during spacing elements of said signals, means for producing a positive pulse upon the transition of said signals from space to mark and a negative pulse during the transition of said signals from mark to space, a first relay actuated by said positive pulse, a second relay actuated by said negative pulse, a third relay actuated under the control of said local source of oscillations, means for synchronizing said local source of oscillations with said signals, a perforator comprising in combination a feed hole punch, a mark punch, a space punch, a punch block actuated upon energization of any of said relays, holes in said punch block, said holes being in alignment with said mark and space punches whereby movement of said punch block causes operation of only said feed hole punch, means actuated by said first relay interposable between said mark punch and the corresponding hole in said punch block whereby movement of said punch block actuates both said feed hole and mark punches, means actuated by said second relay interposable between said space punch and the corresponding hole in said punch block whereby movement of said punch block actuates said center hole and space punches, a tape arranged to be perforated by said punches when said punches are actuated, a tape advance mechanism normally arranged to advance said tape upon each actuation of said punch block and means arranged to disengage said tape advance mechanism when said space punch is actuated.

4. Electrical apparatus comprising in combination a source of code signals having mark and space elements, a local source of oscillations, switching means independent of said source of oscillations for producing a positive potential

during mark elements and a negative potential during spacing elements of said signals, a condenser connected to said switching means, one side of said condenser being arranged to be charged by said potentials whereby pulses of current will flow across said condenser, said pulses being positive at the start of a mark signal and negative at the end of a mark signal, a first relay actuated by said positive pulse, a second relay actuated by said negative pulses, a third relay actuated under the control of said local source of oscillations, means for synchronizing said local source of oscillations with said signals, a perforator comprising, in combination, a feed hole punch, a mark punch, a space punch, a punch block actuated upon energization of any of said relays, holes in said punch block, said holes being in alignment with said mark and space punches whereby movement of said punch block causes operation of only said feed hole punch, means actuated by said first relay interposable between said mark punch and the corresponding hole in said punch block whereby movement of said punch block actuates both said feed hole and mark punches, means actuated by said second relay interposable between said space punch and the corresponding hole in said punch block whereby movement of said punch block actuates said center hole and space punches, a tape arranged to be perforated by said punches when said punches are actuated, a tape advance mechanism normally arranged to advance said tape upon each actuation of said punch block and means arranged to disengage said tape advance mechanism when said space punch is actuated.

5. Electrical apparatus comprising, in combination, a source of code signals having mark and space elements, a first polar relay for producing local oscillations of adjustable frequency, the frequency of said oscillations being adjusted to a period slightly below the dot frequency of said signals, a second polar relay connected in series with the oscillating circuit of said first polar relay whereby said first and second relays oscillate in synchronism, switching means including a third switching means independent of said first polar relay for producing a positive potential during mark elements and a negative potential during spacing elements of said signals, means for producing a positive pulse upon the transition of said signals from space to mark and a negative pulse upon the transition of said signals from mark to space, a first relay actuated by said positive pulse, a second relay actuated by said negative pulses, an oscillating tongue actuated by said second polar relay, a second condenser connected between said oscillating tongue and ground, a source of operating potential, a solenoid actuating relay, said oscillating tongue being arranged to connect said second condenser alternately to said potential and to said solenoid actuating relay, means for synchronizing said local source of oscillations with said signals, a perforator comprising, in combination, a feed hole punch, a mark punch, a space punch, a punch block actuated upon energization of any of said first, second or solenoid relays, holes in said punch block, said holes being in alignment with said mark and space punches whereby movement of said punch block causes operation of only said feed hole punch, means actuated by said first relay interposable between said mark punch and the corresponding hole in said punch block whereby movement of said punch block actuates both said feed hole and mark punches, means

actuated by said second relay interposable between said space punch and the corresponding hole in said punch block whereby movement of said punch block actuates said center hole and space punches, a tape arranged to be perforated by said punches when said punches are actuated, a tape advance mechanism normally arranged to advance said tape upon each actuation of said punch block and means arranged to disengage said tape advance mechanism when said space punch is actuated.

6. Electrical apparatus comprising, in combination, a source of code signals, having mark and space elements, a first polar relay for producing local oscillations of adjustable frequency, the frequency of said oscillations being adjusted to a period slightly below the dot frequency of said signals, a second polar relay connected in series with the oscillating circuit of said first polar relay whereby said first and second polar relays oscillate in synchronism, switching means including a third polar relay actuated by said signals for producing a positive potential during mark signals and a negative potential during spacing signals, a first condenser connected to said switching means, one side of said condenser being arranged to be charged by said potentials whereby pulses of current will flow across said condenser, said pulses being positive at the start of a mark signal and negative at the end of a mark signal, a mark relay, a first rectifier having its anode connected to the other side of said condenser and its cathode connected to said mark relay, a space relay, a second rectifier having its cathode connected to said other side of said condenser and its anode connected to said space relay, an oscillating tongue actuated by said second polar relay, a second condenser connected between said oscillating tongue and ground, a source of operating potential, a solenoid actuating relay, said oscillating tongue being arranged to connect said second condenser alternately to said potential and to said solenoid actuating relay, a phasing coil on said first polar relay, said coil being arranged to slightly increase the frequency of said first polar relay, a third condenser connected between said coil and ground whereby pulses are produced in said phasing coil at the start of a mark signal, a solenoid actuated by said solenoid actuating relay, a feed hole punch, a mark punch, a space punch, a punch block operated by said solenoid, holes in said punch block, said holes being in alignment with said mark and space punches whereby movement of said punch block normally causes operation of only said feed hole punch, a first vane operated by said mark relay arranged to be interposed between said mark punch and the corresponding hole in said punch block whereby upon the actuation of said mark relay and said solenoid both said mark and feed hole punches are actuated, a second vane operated by said space relay arranged to be interposed between said space punch and the corresponding hole in said punch block

whereby upon actuation of said space relay and said solenoid both said feed hole and said space punches are actuated, a tape, said tape being arranged to be perforated by said punches when said punches are actuated, a tape advance mechanism normally arranged to advance said tape upon each actuation of said punch block, and a linkage between said space relay and said tape advance arranged to disengage said tape advance during actuation of said space punch, whereby said tape is not advanced.

7. Electrical apparatus comprising in combination a source of code signals having mark and space elements, a polar relay for producing local oscillations of adjustable frequency, the frequency of said oscillations being adjusted to a period, slightly below the dot frequency of said signals, switching means independent of said polar relay for producing a positive potential during mark elements and a negative potential during spacing elements of said signals, means for producing a positive pulse upon the transition of said signals from space to mark and a negative pulse during the transition of said signals from mark to space, a first relay actuated by said positive pulse, a second relay actuated by said negative pulse, a third relay actuated under the control of said source of oscillations, means for synchronizing said local source of oscillations with said signals, a perforator comprising in combination a feed hole punch, a mark punch, a space punch, a punch block actuated upon energization of any of said relays, holes in said punch block, said holes being in alignment with said mark and space punches whereby movement of said punch block causes operation of only said feed hole punch, means actuated by said first relay interposable between said mark punch and the corresponding hole in said punch block whereby movement of said punch block actuates both said feed hole and mark punches, means actuated by said second relay interposable between said space punch and the corresponding hole in said punch block whereby movement of said punch block actuates said center hole and space punches, a tape arranged to be perforated by said punches when said punches are actuated, a tape advance mechanism normally arranged to advance said tape upon each actuation of said punch block and means arranged to disengage said tape advance mechanism when said space punch is actuated.
